UNITED STATES PATENT OFFICE.

LESLIE P. MICK AND GEORGE WEISS, OF CHICAGO, ILLINOIS; SAID WEISS ASSIGNOR TO
SAID MICK.

PROCESS OF AND APPARATUS FOR DRYING OR DESICCATING LIQUIDS.

1,176,078.

Specification of Letters Patent.

Patented Mar. 21, 1916.

Application filed May 24, 1915. Serial No. 29,983.

To all whom it may concern:

Be it known that we, LESLIE P. MICK and GEORGE WEISS, citizens of the United States, residing in Chicago, county of Cook and 5 State of Illinois, have invented certain new and useful Improvements in Processes of and Apparatus for Drying or Desiccating Liquids, of which the following is a specification.

10 This invention relates to improvements in process of and apparatus for drying or desiccating liquids and semi-liquids, particularly adapted, though not necessarily limited in its use for exhausting the moisture from milk, eggs and other albuminous substances, as well as from starch, malt, and other glutinous liquids, and one of the objects of the invention is to provide an improved process and apparatus of this character for so treating and drying liquids or substances without first necessitating the condensation of the liquid in a vacuum pan, so that the solids are unchanged chemically or physically, while at the same time the 20 solid substances or fluid are brought into a state of fine subdivision and the particles delivered to an extended heated surface of traveling elements, and subjected to heated currents of a drying fluid.

25 A further object is to provide an apparatus of this character having a maximum drying surface and a maximum delivery of the liquid or substance to such surface to be desiccated thereon.

30 To the attainment of these ends and the accomplishment of other new and useful objects as will appear, the invention consists in the features of novelty in substantially the construction, combination and arrangement of the several parts, hereinafter more fully described and claimed and shown in the accompanying drawings illustrating the invention and in which:

Figure 1 is a vertical longitudinal sectional view of an improved apparatus by means of which this improved process may be carried out and as taken on line 1, 1, Fig. 2. Fig. 2 is a left hand end elevation of the apparatus shown in Fig. 1. Fig. 3 is a view taken on line 3—3, Fig. 1. Fig. 4 is a view taken on line 4—4, Fig. 1. Fig. 5 is an enlarged detail sectional view taken on line 5—5, Fig. 6. Fig. 6 is a detail sectional view taken on line 6—6, Fig. 4. Fig. 7 is an 55 enlarged detail view partly in elevation and

partly in section, showing the manner in which the scrapers or deflectors may be secured in position.

Referring more particularly to the drawings, the apparatus shown therein is mounted upon a suitable supporting base, and a shaft 10 of any desired length is rotatably supported in suitable bearings 11, supported by uprights. Arranged upon the shaft 10 are disks 12, which are spaced from each other longitudinally of the shaft 10 by means of suitable spacing elements 13. These disks may be of any desired size, but are preferably about six feet in diameter and may be spaced any desired distance, but good 60 results have been obtained by spacing the disks one inch apart. These disks 12 may be constructed of any desired material and the disks and spacing elements are held against separation so as to rotate with the 65 shaft 10 in any suitable manner such as by means of a collar 14 which is arranged adjacent one end of the series of disks and held against displacement longitudinally of the shaft 10 by means of another collar 15 secured to the shaft. An element 16 is arranged adjacent the collar 14 and also abuts the end disk 12 and this element 16 is preferably in the form of a spider as shown more 70 clearly in Fig. 3. A similar element 17 75 preferably in the form of a spider as shown more clearly in Fig. 2 is mounted adjacent the other end of the series of disks 12 and a collar 18 abuts this element 16. The shaft 10 is provided with a series of threads 19 upon 80 which a collar 20 is threaded so that by screwing the collar 20 on the threads 19 against the collar 18, the disks 12 and the spacing members will be forced tightly into 85 engagement and will be thereby secured to 90 the shaft 10 for rotation therewith.

The shaft 10 may be rotated in any desired or suitable manner, such as by means of a worm wheel 21 connected to the shaft and which meshes with a worm 22, secured to a shaft 23 carrying a gear 24 that meshes with a gear 25 on a shaft 26 and on which shaft 26 is a pulley 27, over which a drive belt 28 passes so that when the pulley 27 is 95 rotated motion will be imparted to the shaft 10. The disks 12 are arranged to rotate beneath a hood or cover 29 constructed of any desired or suitable material and this in turn is covered with a heat insulating material 100 30, and the ends of the cover are supported 110

by end members 31 with which the spiders 16, 17 have sliding engagement.

An inlet 32 is provided adjacent the bottom of the hood, while an outlet 33 is also 5 provided adjacent the hood but spaced from the inlet, and the inlet 32 and the outlet 33 extend in directions lengthwise of the shaft 10 and transversely with respect to the disks 12. The blast of a hot heating fluid is introduced into the hood or casing through 10 the inlet 32, preferably at a temperature from three hundred to four hundred degrees Fahrenheit and is so distributed that the heating fluid will circulate between adjacent 15 pairs of disks to heat the disks and will pass in contact with the disks through the casing and out of the outlet 33.

Arranged adjacent the inlet 32 and between each pair of disks 12 is a deflector 34, 20 which is of a size to substantially fill the space between the adjacent disks 12. These deflectors are so arranged that the heating fluid when entering the casing will be deflected thereby so as to circulate against 25 the disks and through the casing, and similar deflectors 35 are arranged adjacent the outlet 33 for directing the heating fluid therethrough. These deflectors 34, 35 being so arranged as to prevent the heating fluid 30 from making a direct passage from the inlet 32 to the outlet 33.

Arranged preferably adjacent the bottom of the machine and in proximity to the outlet 33 to run lengthwise of the apparatus, 35 is a liquid supply pipe 36 of any suitable diameter, and leading from this supply pipe are a plurality of pipes 37, which extend upwardly between each pair of disks and these pipes 37 contain small perforations 40 on opposite sides thereof and through which perforations, the liquid is delivered to form a thin film on each side of the disks. The liquid is fed through the pipe 36 and pipes 37 in any suitable manner.

45 Arranged between each pair of disks 12, is a scraper 38 for scraping the dry powder from the disks 12. A conveyer 39 is arranged adjacent the bottom of the machine for receiving the powder as it is scraped 50 from the disks and for conveying it away to a suitable point.

This conveyer 39 is here shown as being of the spiral type and is operated in any suitable manner, such as by means of a 55 sprocket chain 40, which passes over a sprocket wheel 41 on the shaft 26 and also over a sprocket wheel 42 on a stub shaft 43, and to which shaft 43 is secured a gear 44 that meshes with a gear 45 secured to the 60 shaft of the conveyer 39. The scrapers 38 and deflectors 34, 35 may be secured in position in any suitable manner, but are each provided with a depending portion 46 that abuts a projection 47 and with which projection 47 a clamping member 48 coöper-

ates, the clamping member engaging the projection 46, and fastening devices, such as bolts and the like 49 are provided for securing the clamping member 48 in position. This securing means obviates the 70 necessity of individually fastening each of the scrapers and deflectors and permits the ready removal of any one or more of the deflectors or scrapers without interfering with the rest.

75 In use, the disks 12 are revolved at any desired speed, preferably at the rate of one complete revolution every two minutes, or just fast enough for the liquid to become thoroughly dry by the time it reaches the 80 scrapers. The liquid to be dried is introduced through the pipes 36, 37 and as the disks are heated by the blast of hot heating fluid, the liquid which is sprayed upon the 85 disks not only contacts with the heated disks, but the hot heating fluid will come into contact with a thin film of liquid which is spread over the large surfaces of the disks. This will cause the steam to be driven off and the moisture which rises from 90 the liquid in the casing will be absorbed by the hot fluid and by contact with the heated disks.

95 The liquid will become thoroughly dried by the time it reaches the scrapers 38 and these scrapers will scrape or remove the fine dry film of powder from the disks and deliver it to the conveyer 39.

The heating fluid entering the machine at 100 the inlet 32 is deflected upwardly by the deflectors 34 and these deflectors are so arranged that they will not contact with the disks to 105 escape the liquid or powder therefrom and this is also true of the deflectors 35, but the deflectors operate to deflect the heating fluid through the upper portion of the mechanism and allow only a small amount to circulate through to the scrapers and conveyer. The deflectors 35 also operate 110 to cause the moisture and steam to be carried away through the outlet 33 and away from the drying zone. The deflectors 35 also perform another function, to-wit: in the event that bubbles arise or form near the 115 point where the liquid is introduced to the disks 12 or should the liquid be delivered to the disks in a manner that would cause the film to be too thick or heavy for practical 120 drying purposes, they will scrape off the thick liquid and will destroy the bubbles, leaving the liquid on the surface of the disks in a thin film so that the heating fluid can easily absorb the moisture therein. The excess liquid delivered to the disks through the 125 pipes 37 may be delivered into a suitable receptacle 50 which is preferably arranged adjacent the supply pipe 36 and the pipes 37, and this receptacle may be provided with an outlet pipe 51.

130 Obviously the liquid may be supplied

through the pipe 36 in any suitable manner. With this improved construction it will be manifest that it is not necessary to first condense milk, (if milk is being dried) in a 5 vacuum pan and that the apparatus is provided with a maximum heating or drying surface. Furthermore, this improved method is much more rapid and economical than the methods and apparatus heretofore 10 employed. and as the liquid is dried by a hot blast of heating fluid, the dry powder will be thoroughly soluble in water and will contain only about two or three per cent. moisture, while at the same time it will be 15 very low in bacteria count.

While the preferred form of apparatus for carrying out this process has been herein shown and described, it is to be understood that numerous changes may be made in the 20 details of construction, and in the combination and arrangement of the several parts without departing from the spirit of this invention.

What is claimed as new is:

25 1. The process of obtaining the solid constituents of liquids and semi-liquids in the form of powder, which consists in directing and confining a current of heating fluid against a plurality of spaced rotating disks, 30 conducting the substance between the disks and spraying it over the lateral surface of the disk, scraping the dry powder from the face of the disk, and discharging the dry powder separately from the heating fluid 35 and vapor.

2. An apparatus for obtaining the solid constituents of liquids and semi-liquids in the form of powder, embodying a plurality of laterally spaced rotating disks, a casing 40 in which the disks are arranged to rotate, means for directing a current of heating fluid through the casing and against the disks, means disposed between the disks for spraying the substance against the lateral 45 faces of the disks, and scrapers operating between the disks for removing the dry powder from the disks.

3. An apparatus for obtaining the solid constituents of liquids and semi-liquids in 50 the form of powder, embodying a plurality of laterally spaced rotating disks, a casing in which the disks are arranged to rotate, means for directing a current of heating fluid through the casing and against the 55 disks, means disposed between the disks for spraying the substance against the lateral faces of the disks, scrapers operating between the disks for removing the dry powder from the disks, and deflectors for the 60 heating fluid, said deflectors disposed adjacent the inlet and outlet of the said heating fluid.

4. An apparatus for obtaining the solid constituents of liquids and semi-liquids in 65 the form of powder, embodying a plu-

rality of laterally spaced rotating disks, a casing in which the disks are arranged to rotate, means for directing a current of heating fluid through the casing and against the disks, means disposed between the disks for spraying the substance against the lateral faces of the disks, scrapers operating between the disks for removing the dry powder from the disks, and deflectors for the heating fluid, one of said 70 deflectors operating to distribute the fluid over the disk surface.

5. An apparatus for obtaining the solid constituents of liquids and semi-liquids in the form of powder, embodying a plurality of laterally spaced rotating disks, a casing in which the disks are arranged to rotate, means for directing a current of heating fluid through the casing and against the disks, means disposed between 75 the disks for spraying the substance against the lateral faces of the disks, scrapers operating between the disks for removing the dry powder from the disks, and means for catching and confining the surplus substance delivered to the disks.

6. An apparatus for obtaining the solid constituents of liquids and semi-liquids in powder form, embodying a plurality of laterally spaced rotating disks, a casing within 80 which the disks rotate, said casing having an inlet for a current of heating fluid and an outlet therefor, said heating fluid during its passage through the casing circulating against the disks, spray pipes disposed between the disks for spraying the substance against the disks, and scrapers disposed between the disks for removing the dry powder from the disks.

7. An apparatus for obtaining the solid constituents of liquids and semi-liquids in powder form, embodying a plurality of laterally spaced rotating disks, a casing within 85 which the disks rotate, said casing having an inlet for a current of heating fluid and an outlet therefor, said heating fluid during its 90 passage through the casing circulating against the disks, spray pipes disposed between the disks for spraying the substance against the disks, scrapers disposed between the disks for removing the dry powder from the disks, and means for catching and conveying away the dry powder.

8. An apparatus for obtaining the solid constituents of liquids and semi-liquids in powder form, embodying a plurality of laterally spaced rotating disks, a casing within 95 which the disks rotate, said casing having an inlet for a current of heating fluid and an outlet therefor, said heating fluid during its 100 passage through the casing circulating against the disks, spray pipes disposed between the disks for spraying the substance against the disks, scrapers disposed between the disks for removing the dry powder from the disks, and means for catching and conveying away the dry powder.

the disks, and means for catching and conveying away the dry powder separately from the heating fluid and the vapor.

9. An apparatus for obtaining the solid constituents of liquids and semi-liquids in powder form, embodying a plurality of laterally spaced rotating disks, a casing within which the disks rotate, said casing having an inlet for a current of heating fluid and an outlet therefor, said heating fluid during its passage through the casing circulating against the disks, spray pipes disposed between the disks for spraying the substance against the disks, scrapers disposed between the disks for removing the dry powder from the disks, and means for catching and confining the surplus liquid substance as it accumulates upon the disks.

10. An apparatus for obtaining the solid constituents of liquids and semi-liquids in powder form, embodying a plurality of laterally spaced rotating disks, a casing within which the disks rotate, said casing having an inlet for a current of heating fluid and an outlet therefor, said heating fluid during its passage through the casing circulating against the disks, spray pipes disposed between the disks for spraying the substance against the disks, scrapers disposed between the disks for removing the dry powder from the disks, and deflectors disposed between the disks and within the path of the heating fluid for directing the fluid about and against the disks.

11. An apparatus for obtaining the solid constituents of liquids and semi-liquids in powder form, embodying a plurality of laterally spaced rotating disks, a casing within which the disks rotate, said casing having an inlet for a current of heating fluid and an outlet therefor, said heating fluid during its passage through the casing circulating against the disks, spray pipes disposed be-

tween the disks for spraying the substance against the disks, scrapers disposed between the disks for removing the dry powder from the disks, and deflectors for the heating fluid, said deflectors disposed between said disks, some of said deflectors operating to regulate the thickness of the film of substance on the disk.

12. An apparatus for obtaining the solid constituents of liquids and semi-liquids in the form of powder, embodying a rotating disk like element, a casing in which the disk rotates, means for circulating a heating fluid through the casing and against the element, means disposed adjacent the lateral surface of the element for spraying the substance against such surface of the element, and a scraper operating against the lateral face of the element for removing the dry powder therefrom.

13. An apparatus for obtaining the solid constituents of liquids and semi-liquids in the form of powder, embodying a rotating disk like element, a casing in which the element rotates, means for circulating a heating fluid through the casing and against the element, means disposed adjacent the lateral surface of the element for spraying the substance against such surface of the element, a scraper operating against the lateral face of the element for removing the dry powder therefrom, and means for receiving and conveying away the dry powder.

In testimony whereof we have signed our names to this specification, in the presence of two subscribing witnesses, on this 21st day of May A. D. 1915.
